UNITED STATES PATENT OFFICE.

GEORGE C. GROFF AND BENJAMIN F. MEHRER, OF PHILADELPHIA, PENNSYLVANIA.

DESIGN FOR A TOBACCO-STAND.

49,487.

Specification for Design.

Patented Aug. 8, 1916.

Application filed May 3, 1916. Serial No. 95,277. Term of patent 3½ years.

To all whom it may concern:

Be it known that we, GEORGE C. GROFF and BENJAMIN F. MEHRER, citizens of the United States, residing at Philadelphia, in the county of Philadelphia and State of Pennsylvania, have invented a new, original, and ornamental Design for Tobacco-Stands, of which the following is a specification, reference being had to the accompanying drawing, forming a part thereof.

We claim:

The ornamental design for a tobacco stand, as shown.

GEORGE C. GROFF.
BENJAMIN F. MEHRER.

Witness:

F. H. JENNINGS.
